BLIND-STITCH ATTACHMENT FOR SEWING MACHINES

Joseph F. Arver, St. Paul, Minn., assignor to Joseph F. Arver and Harold E. Ruttenberg, co-partners, doing business as Hidstitch Company, St. Paul, Minn.

Application November 12, 1936, Serial No. 110,469

9 Claims. (Cl. 112—178)

This invention relates to an attachment for sewing machines and used for the purpose of making certain kinds of stitching known as blind stitches and well known in dress-making, tailoring and garment manufacture in general.

This device further comprises distinct improvements over my U. S. patent application, Serial Number 740,609 filed August 20, 1934.

The mechanisms involved are mounted on and associated with the presser foot bar of a regular sewing machine, the needle bar and the feed fork mechanisms of such sewing machine and provide for a horizontally reciprocable needle action all designed for high speeds and silent action in making blind-strokes of predetermined gage, as hereinafter fully set forth, reference being had to the accompanying drawings, in which:

Fig. 1 is a top view of the needle actuating mechanism of my device as mounted on the presser foot bar and needle bar of a sewing machine, this figure showing the device in operative position over the cloth plate and adjacent table parts of the sewing machine. Fig. 2 is a front elevation of Fig. 1 and showing additionally, in section, certain feed mechanisms below the cloth plate, as on line 2—2 in Fig. 1. Fig. 3 is a left end elevation of Fig. 2. Fig. 4 is a fragmentary view of the outer end portion of a sewing machine table as on line 4—4 in Fig. 2, with the cloth plate removed to reveal certain details of the stitch length regulating means. Fig. 5 is an under side or bottom view as on line 5—5 in Fig. 2 showing certain plunger actuating means of my device. Fig. 6 is a sectional detail view as on line 6—6 in Fig. 2. Figs. 7, 8 and 9 are diagrammatic top views of the successive needle actions and stitch forming steps involved in the use of my device and Fig. 10 is an enlarged sectional view as on line 10—10 in Fig. 4 and showing additionally a piece of cloth 2, slightly in perspective, being stitched.

Referring to the drawings by reference numerals, 1 designates the table or working surface of a sewing machine and in the outer or left end part of which stitching is done in cloth 2 fed and moved rearwardly in direction of arrow 3 (Figs. 1 and 3) under the presser foot of the machine. 4 is a removably fixed cloth plate in common plane with table 1 and which in my device is of special construction and replaces the regular cloth plate of a sewing machine.

5 (in Figs. 2 and 3) designates the lower, outer extremity of the sewing machine head from which project downwardly the usual presser foot

bar 6 and needle bar 7, both reciprocable vertically as in usual sewing machine structure and well known in the art, my device utilizing the needle bar reciprocating action to impart horizontal needle reciprocation in a plane parallel to the table 1 and over its cloth plate 4. Said needle action provides successive penetrations of the cloth 2 the latter being fed across the cloth plate by the usual feed bar 8 which reciprocates under the cloth plate, being raised during rearward movement for its serrated feed dogs 8D to contact and feed the cloth rearward between cloth penetrating actions of the needle. During forward movement of the feed dogs and bar they are lowered and the dogs are inactive until again raised for next cloth moving step. Said feed bar, the feed dogs, and manipulating means therefor are well known in the art but herein described and illustrated for the purpose of disclosing their synchronized action and relation to various parts 20 of my improved device.

My device involves a special presser foot member comprising an L-shaped plate 9 elongated in direction transversely of the direction of the cloth movement, its vertical arm comprising in part a socket 9A in the bore of which the lower end of the presser foot bar 6 is removably retained as at 9B.

The vertical part of said presser foot comprises further a vertical wall or plate 9B' (see Fig. 2) against the front face of which is slidably engaged a horizontally reciprocable plate 10 by such means as a pair of button-head screws 11 or equivalent thereof at the upper edge of plate 10, other means hereinafter described guiding the lower edge part of plate 10 slidably where the upright and horizontal plate parts of the presser foot member converge. The numeral 9 herein-after designates the elongated lower plate of the presser foot member.

The needle 12 is removably and adjustably fixed parallel and close to the upper side of plate 9 its point directed toward the left (see Figs. 1 and 2) penetrating the cloth 2 which is humped upwardly in the path of the needle by means of a vertically reciprocable plunger 13 mounted below the cloth plate 4 and projectible upwardly therethrough in timed relation to the needle action, said timed action of the plunger being accomplished by means of the feed bar action as will presently be described. The upper end of the plunger 13 is formed in its left half as a shoulder 13S and is right half rounded downwardly from the diametrical top edge thus formed, said top edge provided at the middle with

a notch 13N traversed by the needle during each cloth penetrating action.

9S (Fig. 2) is a slot in the presser foot plate 9, vertically over the upper end of plunger 13 and 5 so located that the squared shoulder part of the plunger is projected upwardly thereto and projecting the cloth upward accordingly over and on the said upper end of the plunger and in the path of the needle 12 as the presser foot comes 10 down and the needle comes forward (to the left) and simultaneously penetrates the cloth thus raised in two places, one at each side of the notch of the plunger (see Figs. 2 and 10). The dash line 12 in Fig. 10 designates the path of the 15 needle and most clearly shows the cloth penetrating action.

Subsequently as the needle is withdrawn, during movement to the right, the presser foot 9 is raised by upward movement of the feed dogs 8D 20 the plunger 13 moves down and the feed dogs move the cloth readwardly one stitch length.

The plunger 13 is retained in a bore of a vertically disposed block 14 secured at 15 to the under side of my special cloth plate 4 said bore being 25 enlarged in lower part of the block to permit a compression coil spring 16 about the plunger yieldably pressing the plunger downwardly, the plunger extending out of the lower end of the block and its exposed lower end continuously and 30 yieldably contacted by a roller 17. Said roller is mounted at the free end of an arm 18 bearing upwardly yieldably by means of a spring 18S, the other end of said arm pivotally connected at 19 to the lower free end of an inverted L-shaped 35 actuator lever 20 the upper end of which is pivotally secured at 21 to housing 14. At the elbow of said actuator lever is fixed a roller projection 20R (see Figs. 2, 3 and 5) bearing upwardly and contacting the stem part of a T-shaped cam 22 40 secured on the under side of a plate 23 fixed at 24 to the feed bar 8 (see Figs. 2 and 5) and extending in horizontal plane to the left from said bar. This fixed plate 23 is pivotally connected at 25 to a lever 26 comprising an elongated flat metal bar 45 under the cloth plate 4 and pivotally connected to the latter near its outer end on a pivot 27 on which it has a limited vertical free action. Said lever 26 extends inwardly, riding freely on top of the feed bar 8 (see Fig. 2) and its inner end carries 50 slidably and pivotally, as at 23P (Fig. 4), an integrally formed cloth feeding dog 8D guidingly retained in slots 4S in the cloth plate 4. The lever 26 and its dog 8D are of course reciprocated by motion of the feed bar 8 through its plate 23 and 55 pivot 25 in the lever 26, said pivots 25 and 23P having slidably mounting, to permit straight reciprocating action of the feed dog 8D and plate 23.

The slight vertical freedom, of parts just described, on pivot 27 is to allow the feed dogs to 60 move up and down with the feed fork.

It will now be understood that the cam action of the T-shaped cam 22 contacting roller 20R while reciprocating over the latter, provides a certain rise and fall of said roller, which movement transmitted to lever 20 causes the latter to swing at its lower end and oscillates the roller 17 in vertical plane, the roller in turn raising the plunger 13 at correct time for the cloth penetrating action previously described. Release of said 65 cam contact with roller 20R allows spring 16 to function and pressing the plunger down out of the path of the needle, this taking place and the plunger remaining retracted as the cloth is moved rearward each step or stitch.

75 The needle reciprocating means are entirely

over or above the cloth plate, being actuated directly by the needle bar, which action is of course synchronized with the cloth feeding means described. I will now describe in detail the needle action means.

The reciprocable upright plate 10 is provided intermediate its ends with a diagonal slot 10S engaged by a suitable horizontal projection 28P of the block 28 removably secured as at 29 to the lower end part of the needle bar 7. The length 10 of slot 10S, extent of reciprocation of the needle bar 7, determines the horizontal stroke of plate 10. The needle is preferably clamped at its heavy end in the horizontal base 30B of an L-shaped bracket 30 the vertical part of which is adjustably 15 retained flat against the forward face of plate 10 near its right end, said adjustable means comprising an upper eccentric screw 31 and two lower screws 32 (see Figs. 1 and 2) the latter passing through slots in the bracket 30. Adjustment of 20 eccentric 31 and screws 32 enables an operator to set the needle accurately or as needed to traverse the notch in the plunger 13. It will be understood of course that the needle point is directed toward the left.

33 is a thread extending from a spool (not shown) to a tension wheel 34 (Fig. 2) on the machine head, thence down to and through an aperture 30A in clamp 30, thence along the under side of the needle and up through its eye (see Figs. 30 2, 7, 8 and 9).

35 is a flat metal block fixed transversely on the base plate 9 this block being L-shaped and having an arm 35A fixed in parallel relation to the inner edge and upright part of 9B to slidably 35 guide and retain the lower edge of plate 10 therebetween. The central part of said transverse block is in the path of the needle and is notched at its under side to permit reciprocation of the needle therein, as at 35N in Fig. 6, where an X in 40 the notch indicates the needle position. During stitch forming operations the needle point is reciprocated through said block and past it to the left and under an oscillatable finger plate 36 in co-operation with which the needle acts to make 45 and inter-lock thread loops at the left side of the plunger where the needle emerges at each penetration.

The loop forming finger plate 36, hereinafter designated the looper is an elongated flat metal 50 plate pivoted on and near the left end of base plate 9 as at 37 (see Figs. 1, 7, 8 and 9) and directed toward the right therefrom its latter end formed with a forwardly directed, tapered and suitably curved finger 36F which is oscillated 55 across the path of the needle point and said entire finger plate is normally spring pressed rearwardly by any suitable means such as the wire spring arm 38 fixed in a post 39 on base 9. The looper bears rearwardly continuously against a 60 cam bar 40 fixed as at 41 on the lower inner face of the slide plate 10, the said bar having a cam shoulder 40S near its right end. An upright peg 36P on the looper engages said cam bar and as the plate 10 reciprocates the said pin rides the cam 65 bar causing the looper to be oscillated when riding the shoulder 40S, thus oscillating the finger 36F across the path of the needle and directly over it. This looper member may have reciprocating action instead of oscillating or any equivalent 70 thereof.

Assuming now that the needle is about to make a penetration of the cloth 2 starting from extreme right position (Fig. 7) the looper 36F is at this time in extreme forward position. The 75

needle first moves to the left to contact the cloth (dotted position Fig. 7) and plunger 13 is upholding the cloth in inverted U or V form in the path of the needle which penetrates the 5 cloth to the right of the plunger then passes to left in the notch of the plunger and pierces the cloth also in the path of the needle at the left side of said notch. This action brings the needle point, with two bights of thread, out to the left 10 as the looper 36F is moved rearward over the needle as peg 36P at this instant rides back on shoulder 48S of cam bar 40. In Fig. 8 the looper finger is directly over the needle and in Fig. 9 it is clear of it rearwardly with its 15 prong directed toward the upper adjacent side of the needle. As positioned in Fig. 9 the needle is at extreme left position, exposing one bight of the thread on top of the needle and another bight under it.

20 Now when the needle starts back (to right) the thread on top of it is made slack and finger 36F starting forward enters between said thread and the needle and as the latter is retracted out of the goods the cloth is fed back one step by 25 the feed bar 8, the finger 36F retains the thread on it in the form of an elongated loop (designated 33L in Figs. 7, 8 and 9) extending from the just completed cloth penetration and forward, the forward end of said loop remaining 30 on the finger and becomes slack when the looper starts to move back on the shoulder of the cam bar 40 and said loop is penetrated by the next forward movement of the needle, the said thread loop being released from the finger by its movement to the right caused by the thread of the 35 loop being guided to the right by the needle contact and the edge of an aperture 35A' in the transverse plate 35 and the rearward movement of the cloth by the feed fork. 9S is a slot in 40 plate 9 registering vertically with aperture 35A' just described (see Figs. 1 and 2).

Thus there are two strands of thread in each cloth penetration, and one strand at the right from one penetration to the next, while on the 45 left is formed a row of interlocked thread loops 33L in a row parallel to the single strands, forming the blind stitching.

The yieldable spring and roller actuated plunger 13 automatically compensates for varying thickness of goods passing over the plunger and the needle in any case penetrates the goods so closely to the underside of the goods that when the goods are removed from the machine the said points of penetration reveal little or 55 none of the thread on said side. If thread is used of a color similar to the color of the goods the penetrations are to all intents and purposes invisible, a desirable feature in certain garment manufacture.

60 In Fig. 10 a folded hem of a piece of goods is shown in the process of being blind-stitched and illustrating that the looped parts of the blind stitches are completely hidden when the goods are flattened out, and to the left in said 65 Fig. 10 is shown a row of stitches exposed on a single thickness of cloth.

My presser foot has a slight vertical action corresponding to that in standard sewing machines and the feed bar and dogs have corresponding functions and are timed for proper action as is well known in the art.

In Figs. 2, 3 and 6, 9R designates a transverse rib on the under side of the presser foot plate 9 and in proximity to the plunger, this for the 75 purpose of engaging and alining the goods being

stitched in proper relation to the penetrating action or in other words it is an auxiliary medium for feeding and guiding the goods accurately.

Referring again to the vertically reciprocable plunger 13 and its yieldable upward pressure, 5 said pressure as described, automatically engages any thickness or thicknesses of cloth or various kinds of cloth and the correct relative position or location of the notch in the plunger and the needle path therethrough is maintained.

This assures minimum exposure of thread on 10 right side of the goods. It is clear that upward movement of the plunger brings the angle of its shoulder directly under the presser foot plate.

It will be readily understood that the stitching 15 action of my device may be reverse to that shown, or from left to right and other mechanical details within the scope and spirit of my invention may be used.

I claim:

1. A blind-stitch attachment for sewing machines having a vertically reciprocable presser foot bar and a vertically reciprocable needle bar, a cloth plate and table in common plane therebelow, a reciprocating feed bar and feed dogs 25 actuated thereby and projectible through the cloth plate to contact and feed cloth rearwardly under the needle bar, the action of said feed bar synchronized with relation to the needle bar; said attachment comprising over the cloth plate 30 an elongated presser foot of L-shape in cross section and removably fixed on the presser foot bar, a vertically disposed needle actuator plate 35 slidably retained in parallel relation to the vertical part of the presser foot, means on the 40 needle bar for engaging said actuator plate and imparting horizontal reciprocating movement to the said actuator plate, means on said actuator for adjustably and rigidly retaining a needle in parallel relation to it, at its base and in proximity 45 to the presser foot base, means mounted at the under side of the cloth plate including an upright plunger projectible upwardly yieldably in the path of the reciprocating needle to press goods to be stitched upwardly in ridge formation 50 over the cloth plate, said plunger notched centrally and traversed by the needle penetrating the goods at both sides thereof, said needle threaded to penetrate the goods with a double bight thereof and means mounted on the presser 55 foot to engage the thread near the point of the needle and form successive interlocked loops of thread in a row on the surface of the goods where the needle point emerges.

2. The structure specified in claim 1, said 60 plunger formed at its top end with a shoulder, said presser foot having a slot toward which said shoulder part is projected by the upward movement of the plunger.

3. The structure specified in claim 1, in which 65 said actuator plate reciprocating means comprises a block fixed on the lower end of the needle bar of the sewing machine, said actuator plate being provided with an inclined slot slidably engaged by said block.

4. The structure specified in claim 1, in which 70 the direction of reciprocating movement of the needle is transversely of the direction of the action of the feed bar and feed dog action of the sewing machine.

5. The structure specified in claim 1, and an 75 oscillatable cloth-feed lever member pivoted at the underside of the cloth plate near its outer end and extending toward and over the sewing machine feed bar, a feed dog member carried

by the free end of said lever said feed dog provided with serrated parts projectible through and guided in slots provided in the cloth plate, and a slotted pivotal connection in said feed dog end 5 part, a plate rigidly secured to the feed bar and having a variably adjustable pivot connection with said cloth feed lever intermediate the ends of the latter, to provide selective feed dog movement for stitch lengths as required.

10 6. The structure specified in claim 1, and an oscillatable cloth-feed lever member pivoted at the under side of the cloth plate near its outer end, extending toward and over the feed bar, a feed dog member carried by the free end of said 15 lever, said feed dog provided with serrated parts projectible through and guided in slots provided in the cloth plate, and a slotted pivotal connection in said feed dog part with said lever, a plate rigidly secured to the feed bar and having longitudinally adjustable pivot connection with said cloth feed lever intermediate the ends of the latter, to provide selective movement of the feed 20 dogs, the pivot of said feed dog lever comprising a vertically disposed headed pin longer than the pivot part of the lever journaled thereon, for the purpose set forth.

25 7. A blind-stitch attachment for sewing machines having vertically reciprocable presser foot and needle bars over a sewing table and cloth plate therein, a horizontal and vertically reciprocable feed bar under the cloth plate and means for synchronizing the feed bar movements with relation to the needle bar movements; a presser foot secured on the lower end of the presser foot bar, a vertically disposed actuator slidably retained in said presser foot in proximity to the needle bar, means connecting the needle bar and said actuator to provide horizontal reciprocation of the actuator, a needle holder on said actuator 30 to hold a straight needle in horizontal direction and reciprocable accordingly in a horizontal plane, means for guiding and feeding cloth material under said needle on the cloth plate in a direction transverse of the needle action, plunger means for projecting said material upwardly in 35 the path of the needle in an inverted V-form to cause double penetration of the material by the needle and means for retracting said plunger when the needle is withdrawn from the material, said needle fixed with its eye vertically directed, 40 thread guide means for thread extending under tension from a source of supply and comprising the provision of a vertical aperture in the needle 45

50

holder for the thread to extend downwardly therethrough thence longitudinally under the needle and upwardly through its eye to provide a double bight of thread in the penetrated material, a thread-loop forming finger member manipulated by the actuator plate to engage a bight of 5 said thread over the needle when the latter projects through the material to form a thread loop and retain the same until the needle makes the next penetration, said loop retained in the path 10 of the needle making the next penetration through said loop, and means for releasing said loop from the finger before next loop forming action.

8. The structure specified in claim 7, in which 15 said loop-forming finger member comprises a horizontally oscillatable elongated member pivoted on the presser foot base its free end formed with a transversely arcuate, forwardly directed and tapered finger oscillatable in the path of the 20 needle and over it to engage the thread on top of the needle as the latter is positioned thereunder and the finger point is actuated forwardly.

9. A blind-stitch attachment for sewing machines having vertically disposed, parallel and reciprocable bars, a horizontal table therebelow and cloth feeding means operating intermittently and in synchronization with said bars, a relatively rigid frame mounted on one bar, a needle retaining member slidably mounted in said frame 25 and means mounted on the other bar to produce horizontally reciprocating movement of the needle member, said latter member comprising in part an adjustable needle holding clamp to hold a needle in horizontal direction over the horizontal table, means for feeding cloth rearwardly 30 on the table under the presser foot in successive steps and selective length of movement, and cloth contact means mounted under said table and projectable upward at predetermined intervals to 35 press the cloth upward in inverted channel shape and in the path of the reciprocating needle to provide double penetration of said raised cloth and means mounted on said presser foot member adjacent the extreme forward position of the needle to engage the thread on said needle and form 40 a thread loop during and after retraction movement of the needle, said loop forming means arranged to hold said loop and subsequently release 45 said thread loop during the next penetrating action of the needle.

JOSEPH F. ARVER.
